DESIGN FOR A HOLDER FOR A GLASS COFFEE MAKER

Otto G. Griesbach, Chicago, Ill.

Application January 23, 1939, Serial No. 82,535

Term of patent 7 years

To all whom it may concern:

Be it known that I, Otto G. Griesbach, a citizen of the United States, residing at 841 Wilson Avenue, Chicago, in the county of Cook and State of Illinois, have invented a new, original, and ornamental Design for a Holder for a Glass Coffee Maker, of which the following is a specification, reference being had to the accompanying drawing, forming part thereof.

Figs. 1 and 2 illustrate, respectively, a side elevational view and a top plan view of a holder for a glass coffee maker embodying my new design.

Fig. 3 is a vertical sectional view taken on line 3—3 of Fig. 1.

I claim:

The ornamental design for a holder for a glass coffee maker, as shown.

OTTO G. GRIESBACH.
